DIVIDER BOARD FOR FILING DRAWERS

Application filed November 26, 1929. Serial No. 409,770.

This invention relates to a divider board for the drawers of filing cabinets and has for its object to associate with the board an adjustable shoulder whereby the board may be 5 adapted for use in drawers of different heights and its angular position of adjustment varied to meet different conditions of use. In accordance with the invention a vertically adjustable element is mounted adjacent the upper side of the board and is movable upwardly or downwardly to change its effective height in relation to the edge of the drawer on which it rests when in use. The 10 adjustable element is of simple and inexpensive construction, capable of ready manipulation and engageable positively with the drawer at two spaced points to afford a substantial support. In the preferred embodiment of the invention the board itself 15 is provided adjacent its upper edge with guides in which the adjustment elements are disposed and along which they may slide. A further object of the invention is to incorporate in a divider board an extensible 20 shoulder which may be moved upwardly from the board for engagement with the sides of the drawer to constitute the stops for the board thereby enabling the board itself to be made relatively low in height and of 25 a height wholly independent of the height of the side boards of the drawer.

Reference is now to be had to the accompanying drawings for a detailed description of two preferred embodiments of the invention, in which:

Figure 1 is a view in perspective of several of the improved divider boards disposed within a drawer, the drawer itself being broken away in the interest of clearness.

Figure 2 is a detailed view in front elevation of a board embodying the improvements.

Figure 3 is a detailed view of one of the improved slidable stops.

Figures 4 and 5 are fragmentary views in section taken through the edge of the board shown in Figure 2 and on the planes indicated by the lines 4-4 and 5-5, respectively.

Figure 6 is a view in perspective of a divider board embodying a modified form of the improvements.

Figure 7 is a view in plan of the board shown in Figure 6.

The side boards a' , a'' , of a drawer are indicated in Figure 1 in which drawer may be mounted several divider boards b which in accordance with preferred practice are hingedly supported at their lower edges in spaced relationship, separate plates c carrying the boards being inserted within the drawer as shown. The invention is not concerned with the manner of mounting the boards within the drawer since any suitable means may be employed for the purpose of disposing them in the desired relationship to one another and to the drawer. In accordance with the present invention the divider board b has formed along its opposite edges near the top a channel-way b' or the equivalent. Where, as illustrated, the board b is of sheet metal this channel-way may be inexpensively provided by stamping out extended ears at opposite sides of the board and reversely bending these ears to form the channels as indicated in Figure 4. In one wall of the channel may be formed a series of spaced holes b'' for the purpose to be described. Within each of the channels thus formed is mounted an adjustable stop d illustrated clearly in Figure 3. This stop is preferably made up of a piece of stiff spring wire having one extended straight leg d' , a reversely bent reenforced section d'' and another straight leg d''' in parallelism to the leg d' but formed with an angle extension d'''' at its end. The improved stop is of such a width as to permit the legs d' , d''' , to be received snugly within the vertical channel-way b' . One of the legs d' is adapted to slide freely along one side of the channel-way while the hooked end d'''' of the other leg is adapted to be engaged with any one of the holes b'' in the other side of the channel-way that may be selected. The resiliency of the legs is such that the hook d'''' may be withdrawn readily from any one of the holes and the stop slid upwardly or downwardly to engage the end with any one of the remaining holes. Beneath the channel-ways b' at each side of the divider board b and along the opposite sides edges thereof are formed

guideways for the reenforced section d^2 of the stop. One simple method of providing such guideways is illustrated in Figures 2 and 5. There it will be seen that a flat piece 5 of metal e having a right angle bend therein e' may be secured on the face of the board b so that one portion e^2 will lie in spaced relationship to the board b and their edges be in alignment. The result is a guideway generally in line with the channel-way b' , to receive the reverse bend d^2 in the stop. Such an arrangement gives substantial support for the stop d since its hooked end d^4 engages the channel-way b' and the reverse bend d^2 which 15 is spaced some distance below the hooked end d^4 engages in the guide-way e^2 very snugly. Similarly, the engagement of the straight leg d' with the outer edge of the channel-way b' increases the firm engagement of the stop 20 with the board.

By means of the construction described it will be evident that the divider board b may be readily adapted for use in drawers having side boards of different heights. The stop d 25 is adjusted to the desired elevation whereby when it rests on the upper edge of the side board of the drawer the divider board will be supported in the desired angular position.

Turning now to the embodiment illustrated in Figure 6 not only are all of the advantages of the first form of the invention obtained but, in addition, the modification permits of the use of a board of less height regardless of the height of the side walls of the drawer. In 30 this embodiment the board f is shown as formed with channel-ways f' , f^2 , along its opposite side edges extending downwardly from the top. These channel-ways may be formed conveniently in the manner heretofore described with reference to the channel-way b' . Holes f^3 are also provided in the 35 walls of each of the channel-ways. Stops h of substantially the same form as the stops d are provided in this construction except that 40 these stops are inserted in the upper ends of the channel-ways f' instead of the lower ends as heretofore described. The hooked end h' illustrated in dotted lines may be engaged with any one of the several holes f^3 to determine the effective elevation of the stop while 45 the straight leg h^2 of each stop slides freely on the side wall of the channel-way. In this construction of the stop the reverse bend h^2 is formed oppositely from the hooked end h' 50 so that this reenforced section extends outwardly beyond the straight leg h^2 . This carries the reverse bend beyond the side edge of the divider board f for direct engagement with the top edge of the side board of each 55 drawer. By this construction it will be evident that the divider board itself may be as of little height as will serve the purpose regardless of the relative height of the side boards of the drawer since the adjustable stops h 60 will insure its support at the necessary angle

when they are brought to rest on the upper edges of the side boards.

Both forms described are characterized by simplicity of construction and ease of operation. Changes in the details of design of the channel-ways and guideways and of the stops may be made without departing from the spirit of the invention so long as such changes fall within the scope of the appended claims. 75

What I claim is:

1. A divider board having channel-ways along its opposite edges, stops adjustably mounted in said channel-ways, and means to retain the stops positively in adjusted positions. 80

2. A divider board having channel-ways along its opposite edges, stops adjustably mounted in said channel-ways, and said channel-ways being provided with means to engage the stops positively to maintain them in adjusted positions. 85

3. A divider board having channel-ways along its opposite edges, stops adjustably mounted in said channel-ways, said channel-ways being provided with spaced openings and lugs carried with the stops engageable with said openings. 90

4. A divider board having channel-ways along its opposite edges, and adjustable stops 95 slidable in said channel-ways and comprising reversely bent loops of wire each having two parallel legs engageable with the opposite side walls of the channel-ways.

5. A divider board having ways along its edges and stops adjustably mounted within said ways, each stop comprising a piece of spring wire reversely bent to provide two elongated legs in parallelism, the resiliency of the wire maintaining the legs in slidable engagement at opposite sides of each way. 100

6. A divider board having ways along its edges with openings in the ways and stops adjustably mounted within said ways, each stop comprising a piece of spring wire reversely bent to provide two elongated legs in parallelism, the resiliency of the wire maintaining the legs in slidable engagement at opposite sides of each way, one of the said legs having a hooked end for positive engagement with the said openings in the way to maintain the stop positively in adjusted position. 105

7. In combination with a divider board, stops slidably mounted along opposite vertical edges of the board and movable longitudinally thereof to change the effective height of the stops, and means to maintain the stops positively in adjusted position. 110

This specification signed this 19th day of November A. D. 1929. 115
